small boat, such as a skiff or rowboat, and to provide a means for readily attaching a sailing keel thereto, so that the boat may be converted into a sailing boat, and further to provide a means for readily detaching the keel from the boat, so that the boat may be used in the manner for which it was originally designed, all while the boat is in the water.

UNITED STATES PATENT OFFICE

DETACHABLE SAILING KEEL

Herbert A. Geisler, Bristol, R. I.

Application October 23, 1948, Serial No. 56,081

2 Claims. (Cl. 114—140)

1

This invention relates to an improvement in a detachable keel for a small boat.

Heretofore it has been proposed to provide a keel for a rowboat or similar small boat wherein the boat may be converted into a sailing boat. Such a sailing keel is attached to the boat in a manner which usually requires raising the boat from the water or turning the boat over on shore to have access to the bottom thereof in order to attach the keel thereto. It is desirable to provide a sailing keel which may be readily attached to the bottom of a rowboat to convert the same into a sailing boat and wherein the keel may also be readily detached from the boat so that the boat may be used in the manner for which it was originally designed, all while the boat is in the water.

An object of the invention is the provision of a sailing keel and manner of attaching the same in place, so constructed as to secure the desirabilities mentioned above.

Another object of the invention is the provision of a sailing keel of the above character which may be manipulated in and out of position on the bottom of a boat from the stern of the boat.

A more specific object of the invention is to provide a sailing keel of a buoyant nature wherein the buoyancy thereof will aid in positioning the same when attaching the same to the boat.

With these and other objects in view, the invention consists of certain novel features of construction, as will be more fully described and particularly pointed out in the appended claims.

In the accompanying drawings:

Figure 1 is a side elevational view of a skiff or rowboat equipped with a sailing keel embodying my invention;

Figure 2 is a perspective view of the bottom of the boat turned upside down to more clearly show the keel and the means for attaching the same to the bottom of the boat;

Figure 3 is a plan view of a fragmental portion of the boat bottom also showing the keel and the means for attaching the same to the bottom of the boat;

Figure 4 is a perspective view of the keel;

Figure 5 is a sectional view taken substantially along the lines 5—5 of Figure 3; and

Figure 6 is a sectional view taken substantially along line 6—6 of Figure 3 showing the manner in which the keel attaching means are secured to the bottom of the boat.

In proceeding with the invention, I provide a socket on the bottom of a small boat into which one end of a removable keel may be placed, while

the other end of the keel may be detachably secured at an accessible location at the stern of the boat while the boat is in the water. The keel may be made of any various suitable material, preferably of wood in order that the same may be buoyant to aid in positioning and attaching the same from the boat.

Referring to the drawings for a more detailed description of the invention, 10 designates generally a rowboat or the like to which is attached a sailing keel embodying my invention. The boat is of a usual construction having a bottom 11, sides 12, stern 13, and a bow 14. The bottom 11 carries spaced similar strips 15 and 16, preferably made of wood, and tapered from either side of the center toward the end thereof. These strips are secured in spaced relation to the bottom of the boat by means of bolt and nut fastening 17, best shown in Figure 6. Thus, there is provided a channel 18 extending longitudinally of the bottom of the boat substantially centrally thereof. The forward end of the channel extends to near the bow 14 and a nosepiece 19 abuts against the adjacent edges of the strips 15 and 16 and is of greater height providing a shoulder 20. A plate 21 extends across the channel 18 and contacts with the shoulder 20. The marginal edges of the plate are secured to the strips such as by fastening means 22 which may be screws or other similar devices. Thus, a pocket 23 is formed at the forward end of the channel 18. The other end of the strips 15 and 16 extends to the stern 13, and each is provided with an opening 24 aligning with each other.

I preferably make the sailing keel 25 of wood in one piece shaped so as to provide centrally thereof a substantial trapezoidal-shaped fin 26 and a reduced forward portion 27. The other end of the keel is provided with an opening 28, which, when the keel is in position, will align with the openings 24 in the strips 15 and 16. The keel is also provided on either side thereof with spacer strips 30 which also function to more or less strengthen the keel.

The keel is slidably related to the channel with the reduced portion 27 received in the pocket 23 in interlocking relation therewith. With the keel in the proper position in the channel, a pin 31, which in the present instance is in the form of a usual cotter pin, is inserted through the now aligned openings 24, 28 to lock the keel in the channel. The spacing between the strips is such that the keel is loosely received therein to facilitate the sliding of the keel in the channel and

also to provide for any swelling of the keel 25
or the strips 15, 16.

In attaching the keel to the boat, the keel is placed in the water with the forward end thereof next to the stern 13 and in line with the channel, the buoyancy of the keel aiding in positioning the keel in this relation to the boat. The keel is next pushed into the channel to position the reduced portion 27 within the pocket 23. With the keel in proper position the openings 24, 28 10 will be aligned and the pin 34 may be inserted through these openings to lock the keel in the channel. All this may be readily accomplished by a person leaning over the stern of the boat and reaching into the water to manipulate the 15 keel in or out of the channel 18.

I claim:

1. In a sailboat, means forming a channel on the bottom of the boat extending longitudinally from the stern to adjacent the bow of the boat, 20 means at the forward end portion of the channel to provide a pocket, a detachable keel having a sliding relation within said channel and provided with a reduced forward end portion received in said pocket and a detachable means at the stern 25 end portions of said channel to lock the reduced end in the pocket and the keel in the channel.

2. In a sailboat, spaced guide strips secured to the bottom of the boat and of a length to extend longitudinally from the stern to adjacent the bow of the boat providing a downwardly opening channel, means to close the forward end of said channel to provide a pocket having side, top, and bottom walls and open in continuation of said channel, a detachable keel having a sliding relation within said channel and having a reduced forward end portion received in said pocket and a removable pin extending through said strips and said keel at the stern end portion of the keel.
